UNITED STATES PATENT OFFICE

145,378

DESIGN FOR A RUBBER HEEL

Earl Bunting, Winchester, Va.

Application May 1, 1946, Serial No. 129,181

Term of patent 14 years

(Cl. D7—5)

To all whom it may concern:

Be it known that I, Earl Bunting, a citizen of the United States, residing at Winchester, in the county of Frederick and State of Virginia, have invented a new, original, and ornamental Design for Rubber Heel, of which the following is a specification, reference being had to the accompanying drawing, forming a part thereof.

Figure 1 is a bottom plan view of a rubber heel, showing my new design;

Figure 2 is a top plan view of the rubber heel shown in Figure 1;

Figure 3 is a vertical section taken on the line 3—3 of Figure 2; and

Figure 4 is a rear elevational view of the rubber heel shown in Figure 1.

I claim:

The ornamental design for a rubber heel, as shown.

EARL BUNTING.
